COOLING SYSTEM FOR INTERNAL
COMBUSTION ENGINES

James A. White, Lockport, N. Y., assignor, by
mesne assignments, to General Motors Corpora-
tion, Detroit, Mich., a corporation of Dela-
ware

Application July 5, 1932, Serial No. 620,852

3 Claims. (Cl. 137—68)

This invention relates to cooling systems for internal combustion engines. More particularly it has to do with a conventional type of circulating system with which is associated an overflow tank for temporarily storing cooling medium expelled from the main system, until such time as it is needed to replenish the supply and maintain the system at full capacity for maximum efficiency.

In the conventional cooling system, water or other liquid coolant is forced by an engine driven pump through a circuit, which includes an air cooled radiator and a jacketed cylinder block, and the heat taken up or absorbed in the jacket is dissipated or transferred at the radiator to an air stream flowing therethrough. As the temperature of the cooling water increases, its volume expands and the coolant in excess of system capacity is discharged through an overflow pipe. Losses also occur because of evaporation, particularly where an anti-freeze solution of low boiling point is used. Water is often forced out of the system in large quantities because of after boiling. After boiling occurs when the engine is suddenly stopped after a hard run, when both the forced circulation of water through the system and air flow through the radiator are cut off. The large amount of heat remaining in the engine block and the water in the jacket being stagnant sometimes results in the formation of steam and a greatly increased expansion. Unless provision is made for receiving the overflow and returning it when the parts cool off, the water in the system will be low when the engine is operated again and proper and adequate cooling will not be had.

With these things in mind, it is here proposed to provide an auxiliary circuit, which includes a storage reservoir connected with the usual overflow pipe in the main system and having an outlet, preferably connected with the main system on the suction side of the pump, or between the pump and the return side or outlet header of the radiator. With this construction, excess water or vapor leaving the main system will not be lost but will be drawn back by the pump whenever occasion requires, thus eliminating the need for constant care and attention to the cooling system and frequent replenishment of the supply and also effecting a savings in those cases where costly cooling solutions are employed.

The particularly important feature of the present invention is the provision of a double acting valve controlling communication between the overflow tank and the main system, and which operates automatically to prevent liquid reaching and filling the overflow tank and the consequent

introduction into the system as a whole of an over supply when the system is being filled, and to prevent air being sucked by the pump and drawn into the main system from the vented overflow tank during periods of normal operation.

The invention will be best understood upon reference to the accompanying drawings, wherein Figure 1 is a rear elevation of a radiator having an overflow tank built in as an integral part thereof; Figure 2 is a side elevation, partly in section, showing the radiator connected with the engine jacket; Figure 3 is a sectional view taken on line 3—3 of Figure 1; Figure 4 is a sectional view of an alternative form of valve; Figure 5 is a detail perspective view of a valve element employed in the Figure 4 structure; Figure 6 is an elevational view illustrating the installation of the overflow device applied as an accessory for existing systems; and Figure 7 is a vertical sectional view of the tank shown in Figure 6.

Referring to the drawings, the reference numeral 1 indicates a core or cooling unit of a radiator assembly, enclosed within the ornamental shell 2. On its underside, the core is provided with an outlet header 3 having an elbow fitting 4 to which may be connected a drain valve 5. The fitting 4 communicates through a hose coupling 6 with a pump casing 7. The pump shaft, which may be driven by a belt from the engine crank shaft, also carries a fan 8 for inducing an air stream through the radiator core 1. Associated with the outlet from the pump is the jacket forming a part of the cylinder block 9 and being connected by the hose coupling 10 with a fitting 11 extending through a wall of an outer tank 12 and opening into an inner tank or inlet header 13 at the top of the core. A short length of pipe 14 extends through the outer tank 12 and connects the inner tank 13 with the filler spout 15 mounted above the tank 12 and closed by a filler cap 16. The two tanks 12 and 13 communicate with each other by an overflow pipe 17 having one end extending into the filler spout 15 and its opposite end into the tank 12 with its intermediate portion of relatively great length, extending downwardly beside the core, and having a reversed loop 18 at its lower end. Extending from the upper portion of the reserve tank 12 is a vent pipe 19, which also constitutes an overflow and which may terminate at any convenient point, but preferably near the bottom of the radiator assembly. Connected at the bottom wall of the reservoir 12 is one end of a return pipe 20 whose opposite end may be suitably connected with the outlet from the radiator as by

means of the fitting 6 on the elbow 4. In the return line 20 at any convenient point, there may be inserted a double acting valve device, such as illustrated in Figure 3, where the valve housing 21 is divided by a partition wall 22 into a pair of intercommunicating chambers 23 and 24. In each chamber is located a float valve which may comprise in each case a body 25 of cork or the like, carrying on its upper side a button or plate valve 26 and on its underside a plate valve 27. When both corks are at rest, as illustrated by the full lines in Figure 3, the plates 27 overlie and close apertures in the bottom walls of the respective compartments, and when the floats 25 are elevated to the broken line positions the valves 26 close openings in the top walls of the two chambers.

When the construction described is in use and it is desired to fill the system with water, the closure cap 16 is removed and water poured into the filler 15. As the level rises in the main system it also rises in the return line 20, and when it reaches the height of the valve casing, the liquid buoys up the floats 25 to seat the valves 26. In this connection, it might be mentioned that the use of the two floats is a safety measure intended to insure operation in the event one or the other should stick. With the valves 26 or either of them, thus seated no water can pass into the expansion tank as the filling continues and the water reaches proper level in the filler spout. When this occurs, the cap is replaced and the engine is ready for operation. As soon as the engine is started the pump draws water through the coupling 6 from the radiator and forces it through the engine jacket and into the upper header 13 for passage through the radiator core, where the heat taken up by the engine is extracted. Under suction of the pump, the water in the return line 20 below the valve is drawn into the main system, whereupon the floats 25 no longer being buoyed come to rest and close the return line against the passage of air from the vented overflow tank. This serves to prevent the main system from becoming air-logged. As the temperature of the water in the system increases there will be a tendency for steam vapors to rise into the filler neck from the top tank and pass through the overflow pipe 17 into the expansion tank 12. Because of the length of the pipe and also because there will usually be a certain amount of water trapped in the loop 18, the steam vapors will be condensed in their passage through the pipe so that there will be little or no loss through the vent 19. Should the water expand beyond the capacity of the main system, or in the event an after boiling surge takes place, the excess liquid rising in the filler neck passes through the overflow 17 and spills out into the reservoir 12. If the expansion exceeds the capacity of the overflow tank any excess water will enter and be discharged by the vent pipe 19. However, the size of the overflow tank may be such that its capacity is equivalent to the ordinary volumetric increase, so that the level in the auxiliary tank ordinarily would not reach the top of the vent pipe 19. The water temporarily stored in the reservoir is free to immediately pass through the return line 20 and into the main system whenever the system needs replenishment. In its passage through the return line no interference is offered by the valve, inasmuch as the valve will first tend to be buoyed up to close the inlet to its compartment but as the water leaves the

compartment the valve again drops down to allow more liquid to pass. With the above explanation it will be apparent that water in the main system is conserved and the necessity for refilling practically eliminated. It follows too that the circulating system will operate at full capacity regardless of the temperature of the liquid therein.

An alternative form of valve is illustrated in Figure 4 and this valve may be substituted for that shown in Figure 3 without in any way changing the function and operation of the parts. In Figure 4 a hollow float ball is indicated at 30 enclosed within a chamber formed by a cylinder 31 closed at opposite ends by shouldered caps 32—32, which support at opposite ends of the chamber a spring valve device comprising an outer circular rim or ring 33 having a spiral finger 34 terminated at the center in an enlarged head or valve element 35. Each cap 32 also carries a fitting 36, which projects through the wall thereof and terminates at its inner end in a seat for the adjacent valve member 35. In full lines in Figure 4, the normal position of the parts is illustrated, wherein the ball float 30 is at rest and bears on the lower spring valve 35 deflecting it into contact with its seat on the fitting 36, sealing the return line to preclude sucking in air from the vented tank. Upon a rise of water into the valve chamber, the float will be buoyed up until it assumes the illustrated broken line position, in which it moves the upper valve 35 into seating engagement over the end of the inlet fitting 36.

To apply the invention to those vehicles already on the market, it is proposed to provide as accessory equipment the expansion tank illustrated in Figures 6 and 7, which may be conveniently mounted on the vehicle dash or at any other suitable point beneath the engine hood. In this construction a vent pipe 40 communicates the upper portion of the tank 41 with atmosphere and an inlet pipe 42 may be connected by tubing 43 with the customary overflow pipe 44 of the radiator. Any of the steam or overflow of the main system will pass through the overflow pipe 40 and into the tank 41 for temporary storage. When needed to replenish the supply in the main system, water may pass out the bottom of the tank through the valve compartments 45 and the pipe line 46 conveniently tapped into the main circulating system on the suction side of the pump as for example at the flexible hose coupling 47. In the valve compartments 45 there may be positioned floats 48, corresponding to the float device as heretofore described and which when at rest, seal the return line against passage of air therethrough and which when buoyed up prevent the back flow of water from the cooling system and into the tank. In this particular installation the upward seating of the valves 48 not only prevents over filling of the main system but it also prevents losses from the main system as might tend to occur because of the fact that the top of the vent pipe 40 is considerably below the normal liquid level in the main system.

I claim:

1. For use in the return line between an engine cooling system and a vented overflow tank for the system, a valve comprising a casing, domed cap pieces at opposite ends of the casing to provide a chamber for insertion in said return line, pipe fittings carried by the cap pieces and extending into the chamber, a substantially flat disc secured between each cap piece and the casing and provided with a spiral slot to afford a spring finger termi-

- nating in a valve adapted to seat on an adjacent fitting to close the opening therethrough, and a float within the casing between said valves, adapted through its gravity weight to spring the lower valve into closed position and preclude the passage of air from the vented tank to the system and through its buoyancy to spring the upper valve to closed position and preclude reverse flow of liquid in the return line.
2. A valve device for a conduit connecting a closed engine cooling system and a vented tank, including a closed chamber having an inlet adapted to communicate with a tank and an outlet adapted to communicate with a system, a pair of valves, flexibly supported by the walls of the chamber, one for closing the inlet against liquid flow back to the tank and the other for closing the outlet against air flow from the tank, means flexibly supporting the valves from the walls of the chamber in normally open relation, and means controlling the action of both valves and comprising a float which moves the valves to closed positions.
3. A valve device for association with the return line between a closed engine cooling system and a vented expansion tank, comprising a chamber having an inlet adapted to be connected with a tank and an outlet adapted to be connected with an engine cooling system, a pair of valves resiliently mounted in the chamber adjacent the inlet and outlet, respectively, and a float device interposed between said valves and adapted when at rest to close the outlet valve against flow of air to the engine cooling system from the expansion tank and when buoyed up to close the inlet valve against the back flow of cooling liquid from the engine cooling system to the expansion tank.
